UNITED STATES PATENT OFFICE

2,422,052

METHOD OF MAKING COLLAPSIBLE TUBES

George W. Temple, Miami, Fla., assignor to Victor Metal Products Corporation, Brooklyn, N. Y., a corporation of New York

Original application July 5, 1941, Serial No. 401,072. Divided and this application May 29, 1944, Serial No. 537,818

4 Claims. (Cl. 29—148.2)

1

This invention is a division of my prior patent No. 2,352,456 and relates to the method of making collapsible tubes of metal such as lead which might contaminate or otherwise injuriously affect the contents, or which might become affected thereby.

Collapsible tubes are customarily extruded in a press from such non-ferrous metals as tin, aluminum and zinc or alloys thereof. In certain cases, lead has been used for the tube where the contents might affect or be affected by other metals. Lead is more abundant and cheaper than the other metals mentioned, but owing to the chemical action upon lead of many ingredients of the pharmaceuticals inserted into collapsible tubes and sold therein, it has not been extensively used for such tubes except under the circumstances referred to.

Even if the tube were extruded by well known processes from a tin-plated or coated slug of lead, finishing operations upon the press-extruded tube, such as trimming and threading the neck of the tube, would cut away the tin coating and undesirably expose the underlying lead.

I have found, however, that a lead tube can be extruded from a tin-coated slug in such a manner that all surfaces of the sandwiched lead are covered with tin. By forming on the neck of the tube at its discharge opening a projecting thin tin-coated cup provided with an end flat closure wall and with a substantially cylindrical wall and then trimming off the end wall to expose the discharge opening, the cylindrical wall with its thin exposed lead edge may be rolled over to carry said exposed edge against the exterior surface of the tube, thereby inexpensively providing a tin-coated lead tube having no exposed lead surfaces.

My invention therefore contemplates the provision of a simple and inexpensive method of making a tin-coated lead or the like collapsible tube provided with a downwardly and outwardly rolled bead, lip or wall arranged outwardly of the discharge opening, and with rolled external screw threads whereby the tube may be extruded, trimmed and finished largely by the usual methods and machinery except for the rolling of the lip and threads which rolling may be accomplished by the use of suitable simple tools rapidly and automatically.

The various objects of the invention will be clear from the description which follows and from the drawing, in which,

Fig. 1 is a fragmentary front elevation, partly in section, of the tube as it appears before the

2

projecting cup thereof has been trimmed and rolled over.

Fig. 2 is a similar view of the tube as it appears with the thin wall rolled into a bead.

In the practical embodiment of the invention which I have shown by way of example, the tube is extruded in a press of the usual type by means of suitable dies. Preferably, a "tin" coated "lead" slug is used from which to extrude the tube. Since the extruding operation is well known, no further description thereof is deemed necessary.

It will be understood, however, that the terms "Lead" and "tin" in this specification means those specific metals as well as any other metals suitable for extrusion from a coated slug into a tube, and that said terms refer to different suitable metals, one adapted to be coated by or sandwiched between layers of the other.

As a result of the extruding operation, the partly finished tube 10 (Fig. 1) is formed, having a thin cylindrical body 11, the thicker tapered conical shoulder 12, the comparatively thick neck 13, (with or without the external screw threads 14 thereon) and the discharge passage 15 closed by the cup-like and very thin projection 16. The formation of said projection is an important intermediate step in the manufacture of my improved tube from two different metals, one metal coating the other. The projection has a preferably flat end wall 17 and a substantially cylindrical wall 18 extending integrally from the end wall to the neck 13 and surrounding the opening or discharge passage 15. The tin coating 19 however covers all surfaces of the tube, both interior and exterior with the heavier lead layer 20 sandwiched therebetween.

After the tube 10 has been extruded in the press, it is mounted on the mandrel of a trimming and finishing machine, where the open end of the tube is trimmed off to cut the tube to the required length, and the threads 14 are rolled in by suitable pressure tools (if the threads have not been previously formed) without breaking the tin coating.

The neck end of the tube is also trimmed and finished. This is done by first trimming off the end wall 17 of the cup-like projection 16 on the line marked "cut" in Fig. 1. Such trimming exposes a lead edge on the wall 18, which of course is undesirable and cannot be left in that condition, owing to the possibility of contact therewith by the tube contents. Consequently, the wall 18 is bent on itself to form a bead and then partly flattened into the position thereof shown in Fig. 2 wherein the extreme end edge 22 thereof is ar-

ranged in contact with the exterior surface of the wall 18 and is protected by the bent part of the wall. The bending of the wall 18 may be accomplished by a rolling operation by means of a suitable tool entering the exposed discharge opening remaining after the end wall 17 has been trimmed off. Such tools may be arranged on the turret of the trimming machine.

The doubled wall or bead 21 resulting from the above-described trimming and rolling operations is forced against the top wall or edge 23 of the tube neck and somewhat flattened, and does not interfere with the threads 14, nor with the cap which may be screwed on the threads. It will be understood that if desired and found convenient, the wall 18 may be rolled inwardly instead of outwardly in an obvious manner. After the tube has been thus finished, it may be subjected to the usual enamelling and capping operations in a manner well known in the art.

It will be seen from the above that I have provided a simple method of making tin-coated lead tubes and particularly for finishing such tubes without exposing any lead surface thereon.

I claim:

1. The method of making a collapsible tube having a neck of a given metal coated with a different metal comprising performing an extruding operation upon a slug of the given metal coated with said different metal to extrude a tube having a body and a neck with a comparatively thin cup-shaped projection extending beyond and covering the discharge opening of the neck, trimming off the end surface of the cup-shaped projection to expose the discharge opening and to form a substantially cylindrical thin wall surrounding said opening, rolling the wall downwardly to arrange the otherwise exposed edge of the wall against a surface of the tube neck, and rolling external threads by pressure into the outer surface of the neck while maintaining the coating unbroken.

2. The method of making a tin-coated lead collapsible tube having a body and a neck com-

prising extruding the body and the neck simultaneously from a tin-coated lead slug while at the same time forming a temporary cup-like projection on the neck, then trimming off part of the projection to leave a wall having an edge in which part of the lead is exposed, and finally bending the wall sufficiently to carry the edge into firm contact with a surface of the tube and thereby to protect said edge against contact with the tube contents.

3. The method of making a tin-coated lead collapsible tube comprising extruding the tube so that it remains tin-coated on all of its surfaces and with a tin-coated cup at one end, trimming off the end part of the cup to leave a wall having an edge in which part of the lead is exposed, rolling the wall over sufficiently to form a bead and to carry said edge into the interior surface of the bead, and rolling threads on the tube while maintaining the tin coating thereof unbroken.

4. The method of making a collapsible tube having an open hollow neck, comprising first extruding the tube and the neck thereof from a tin-coated metal slug so that it remains tin-coated on all of its surfaces while simultaneously extruding a closing wall on the extreme outermost end of the neck, then removing the outermost end part of the neck and the closing wall simultaneously to open the neck, and then bending part of the neck to carry the exposed end edge thereof against a surface of the neck.
